TUBING HEAD

Arthur J. Penick and Kirby T. Penick,
Houston, Tex.

Application April 5, 1935, Serial No. 14,766

5 Claims. (Cl. 285—22)

This invention relates to a tubing head.

The object of the invention is to provide a tubing head adapted to be connected to the top of a casing in a well, and having an opening therethrough for an inner pipe, said opening having an inside diameter not less than, and preferably the same as, the inside diameter of the casing to which the head is attached so as to admit through the head into the casing, tools, or other appliances, without restriction by said head.

Another object of the invention is to provide, in combination with the head, a tubing hanger for suspending a tubing in the well, said head and hanger having ground metallic contacting seats forming a leak-proof joint under ordinary conditions.

Another object of the invention is to provide the combination with a tubing head having a tubing hanger therein, of a novel type of packing ring surrounding and seated on the hanger, with a metal ring on the packing, and a ring nut screwed into the head to retain the packing ring and metal ring assembled above the ground joint, thus providing additional means for preventing leakage up around the hanger.

A still further object of the invention is to provide a tubing head having external threads at its upper end to receive a swaged nipple for the connection of a flow line, or Christmas tree, to the tubing head.

The head is of such construction that upon removal of said nipple and tubing hanger, a conventional blowout preventer may be installed on the head to allow drilling operations to be carried on through the head with safety under conditions of an impending blowout.

With the above and other objects in view, the invention has particular relation to certain novel features of construction, operation, and arrangement of parts, an example of which is given in this specification and illustrated in the accompanying drawing, wherein:

The figure shows a side view of the head, shown partly in section.

In the drawing, the numeral 1 designates a casing adapted to be set in a well bore, and to the upper end of which a tubular head 2 is connected. This head has an internal downwardly converging seat 3, preferably ground smooth, and the inside diameter of the head above said seat is enlarged. The inside diameter of the opening 4 through the head is no less than, and preferably the same as, that of the casing 1.

There is a tubular hanger 5 connected to the upper end of the tubing, or inner pipe, 6. This hanger has the external downwardly tapering face 7 which is also preferably ground smooth, and which rests on and forms a fluid-tight joint with the seat 3 whereby the hanger is supported in the head and supports the tubing beneath.

The upper end of the hanger is externally reduced forming an external upwardly facing shoulder 8, and surrounding said reduced upper end and resting on said shoulder, is an annular packing 9. On this packing is a metal compression ring 10.

The upper end of the head is internally threaded to receive a ring-nut 11 which may be screwed into the head against the ring 10 to compress the packing outwardly against the head, and inwardly against the hanger to form additional means for forming a fluid-tight joint between the hanger and head.

A flowline 12 leads out from the head beneath the seat 3 and is controlled by the valve 13, whereby the flow of fluid through the casing from the well may be controlled.

The upper end of the head is externally threaded to receive a swaged nipple 14, to which a Christmas tree 15, of conventional construction, or other flow-controlling pipe, may be connected.

When the tubing 6 and the Christmas tree 15, or other flow-controlling pipe, are installed, the fluid may flow through said tubing and Christmas tree under the control of the operator.

It is to be here noted that before the well is completed and the tubing and Christmas tree are installed, drilling operations may be carried on through the head 2, and if the circumstances require, a conventional blowout preventer may be screwed on to the top of the head 2 to control the pressure in case a blowout is threatened during the drilling operations.

The inside diameter of the head 2 is such that a drill, or other implement or appliance which the casing will take, may be lowered through the head. In other words, the head 2 is so constructed as not to, in effect, restrict the casing.

The drawing and description disclose what is now considered to be a preferred form of the invention by way of illustration only, while the broad principle of the invention will be defined by the appended claims.

What we claim is:

1. The combination with a tubing head adapted to be connected to a well casing and having

- 5 a minimum inside diameter not less than the diameter of the casing, said head also having an inside downwardly converging annular seat and having its inside diameter enlarged above the seat, of a tubular hanger having an external downwardly converging face shaped to rest on said seat and forming a fluid-tight joint therewith, the hanger being spaced from the head above and beneath the seat, an external annular shoulder on the hanger above the seat, an annular packing on the shoulder fitting closely against the hanger and head, clamp means in the head for maintaining said packing under compression and a swaged nipple closing the upper end of the head and forming a christmas tree connection.
- 10 2. The combination with a tubing head adapted to be connected to a well casing and having a minimum inside diameter not less than the diameter of the casing, said head having its upper end formed with an inside counterbore and also having an inside downwardly converging seat beneath the counterbore, of a tubular hanger having an external downwardly converging face shaped to rest on said seat and forming a fluid-tight joint therewith, the upper end of the hanger being reduced forming an external annular shoulder on the hanger above the seat, an annular packing on the shoulder fitting closely against the reduced portion of the hanger and also fitting closely within the head, clamp means in the head for maintaining said packing under compression, said clamp means comprising a clamp ring on the packing, and a ring-nut threaded into the head and clamped against the ring.
- 15 3. The combination with a tubing head adapted to be connected to a well casing and having a minimum inside diameter not less than the diameter of the casing, said head also having an inside downwardly converging annular seat, and having its inside diameter enlarged above the seat, of a tubular hanger having an external downwardly converging, annular face shaped to rest on said seat and forming a fluid-tight joint therewith said hanger being spaced inwardly from the head except at said seat, an external

annular shoulder on the hanger above the seat, an annular packing on the shoulder fitting closely against the hanger and head, clamp means in the head for maintaining said packing under compression, a tubular Christmas tree connection secured on to and closing the upper end of the head and a valve-controlled flow line leading out from the head beneath said seat.

4. The combination with a tubing head adapted to be connected to a well casing, said head having an inside downwardly converging seat, and having its inside counterbored above the seat and formed with cylindrical inside walls, of a tubular hanger having an external downwardly converging face shaped to rest on the seat and forming a fluid-tight joint therewith, the hanger being spaced from the head above and beneath the seat, an external annular shoulder on the hanger above the seat, an annular packing on the shoulder fitting closely against the hanger and against the head, a metal ring on the packing, a ring-nut threaded into the head and clamped against said ring and a swaged nipple secured on to and closing the upper end of the head.

5. The combination with a tubing head adapted to be connected to a well casing, said head having an inside downwardly converging seat and having its inside counterbored above the seat and formed with cylindrical inside walls, of a tubular hanger having an external downwardly converging face shaped to rest on the seat and forming a fluid-tight joint therewith, the upper end of the hanger being reduced forming an external annular upwardly facing shoulder on the hanger above the seat, and annular packing around the reduced upper end of the hanger and resting on the shoulder and fitting closely against the hanger and against the head, a ring nut threaded into the head and forming means for clamping the packing in place, the upper end of the head being threaded and a swaged nipple screwed on to the head and closing the upper end thereof and forming connection for a Christmas tree.
